FUEL BURNER.

Application filed March 27, 1923. Serial No. 628,014.

This invention relates to liquid fuel burners and has for an object to provide an improved burner which will burn any kind or grade of liquid fuel without carbon deposits; with which combustion will be largely or entirely complete before the gases are discharged; with which all parts of the combustion chamber or passage are readily accessible; which will successfully burn various grades and quantities of fuel efficiently; and which is exceptionally simple, durable, compact, and inexpensive. Other objects and advantages will be apparent from the following description of an embodiment of the invention, and the novel features will be particularly pointed out hereinafter in claims.

In the accompanying drawing:

Fig. 1 is a sectional elevation of a burner constructed in accordance with the invention;

Fig. 2 is a side elevation of the same;

Fig. 3 is a plan of one of the sections of the same; and

Fig. 4 is an elevation partly in section of an ordinary coal burning boiler in which the improved burner has been installed.

In the illustrated embodiment of the invention the burner comprises a hollow body of suitable refractory material, preferably built up of three component sections 1, 2 and 3, the sections interlocking with one another along their abutting edges by a flange and groove. The body is provided with partitions 4 and 5 which divide its interior into a long, continuous, tortuous, enclosed passage or conduit. The passage or conduit opens from the lower face as at A which constitutes the entrance opening, continues upwardly between the partition 4 and the outer side wall, then curves laterally across the top, then downwardly to within a short distance from the lower end of the body. The partition 5 extends between the vertical stretches of the conduit so as to divide the space between these vertical stretches into two additional vertical stretches of the conduit which doubles back upon itself to the upper end, then laterally, and downwardly along the partition 4 separating it from the first mentioned vertical section of the conduit, then laterally across the bottom and upwardly between the other side edge and an extension of the partition 5 to an opening B at the top, which constitutes the exit or discharge opening for the burned gases.

A fuel supply nozzle 7 passes through the uppermost section of the body at the upper end, so as to deposit liquid fuel upon the lateral stretch of the partition 4 where the first section of the conduit travels laterally at the upper end of the burner body. The fuel is conducted from a suitable storage tank through a pipe 8 to the nozzle 7, the flow being controlled by a suitable valve 9 located at a convenient point in the pipe 8.

The uppermost section 3 of the body is provided with an opening 10 just below the fuel nozzle 7, and this opening is normally closed by a suitable closure 11 which is removable to permit of the insertion into the conduit of combustible material, such as waste which has been saturated with a combustible liquid.

In Figure 4 the burner is shown as installed in an ordinary coal burning boiler, the burner being supported upon the grate 12, with the portion of the grate surrounding it closed by refractory material 13. The closure 11 is disposed on the edge toward the door 14 of the boiler, and the fuel supply pipe 8 may be conducted through a notch in the edge of the door to a fuel storage tank arranged exteriorly of the boiler. The damper 15 in the ash-pit door 16 may be utilized as a valve for controlling the admission of air to the burner.

When a burner is to be started, the closure 11 is removed and a quantity of suitable combustible material, such as oil saturated waste, indicated by the reference 17 in Figure 4, is inserted into the tortuous passage just below the fuel nozzle 7. This waste is ignited, after which the closure 11 is replaced so as to close the aperture 10. The natural draught of the chimney to which the flue 18 of the boiler is connected, serves to draw the air through the ash-pit door as controlled by the damper 15 into the ash-pit, then upwardly into the body of the burner through the entrance end of the passage cap A. The air passes upwardly through the passage and supports combustion of the burning waste 17 and then past the fuel nozzle 7.

The liquid fuel is admitted through the pipe 8 to the nozzle 7, and drops upon the lateral stretch of the partition wall 4 and is ignited by the flames and heat from the burning waste. The gases from the burning oil or other liquid fuel pass through the tortuous passage which continues downwardly

for some distance and then doubles back in a reverse direction along the partition wall which separates it from the previous stretches of the passage. These gases pass 5 along the passage in contact with the side of the partition wall 4 opposite that upon which the liquid fuel is deposited, and the heat of the burning gases so heats the partition that the liquid fuel falling upon the 10 heated partition is almost instantaneously vaporized.

The burning gases also pass downwardly in proximity to the entrance stretch of the passage, being separated therefrom only by 15 the partition 4, and the heat from the burning gases is transmitted through the partition to the incoming air so that the air will be preheated to a considerable extent before it reaches the vaporized fuel. The gases then 20 are conducted to the opposite side of the burner body and discharged through the upper end thereof.

The gases leaving the burner body enter 25 the combustion chamber of the boiler, heat the same to a temperature sufficient to vaporize the water in the boiler, and then pass out through the flue 18 to the chimney. It will thus be observed that the entering air 30 is preheated, and that the liquid fuel is deposited upon a heated surface in the presence of a body of preheated air, with the result that practically complete and instant vaporization of the fuel takes place, and 35 consequently practically no carbon will be formed within the passage. However, by separating the sections of the burner body, all parts of the conduit may be inspected or cleaned.

The burning gases are conducted for some 40 distance through the body before passing along the wall upon which the liquid fuel is deposited or along the passage through which the entering air is conducted, because the burning gases must be conducted 45 for some distance before combustion is well under way. Then when the burning gases are conducted along the partition 4 so as to vaporize the fuel and preheat the incoming air, there will be sufficient heat in the burning gases to effectively vaporize the fuel and 50 heat the air to the necessary or desired temperature. With the preheated air and the almost instant vaporization of the fuel, the highest possible efficiency of combustion of 55 the fuel is obtained without carbon deposits, and very heavy grades of fuel may be burned with excellent results.

It will be obvious that with this arrangement 60 the use of blowers, fans or other appliances for producing the necessary draught are unnecessary, the draught of the chimney being relied upon to draw the air through the tortuous passage. The length of the tortuous 65 passage is made of such that the combustion of the fuel is practically complete

before the gases are discharged into the combustion chamber of the boiler, and consequently the gases exert their maximum possible heating effect upon the boiler before passing out through the flues. This also 70 greatly increases the efficiency of the burner.

It will be obvious that various changes in the details, materials, and arrangement of parts herein described and illustrated for the purpose of explaining the nature of the 75 invention, may be made by those skilled in the art within the principle and scope of the invention as expressed in the appended claims.

I claim:

1. A liquid fuel burner comprising a hollow body of refractory material partitioned to provide a continuous relatively long tortuous passage with an air entrance opening in the bottom wall and an exit opening in another wall, the passage extending from the air entrance opening upwardly to the top end, then downwardly to within a short distance of the bottom end, then back between and along the first two stretches in a reverse direction until it reaches the bottom wall, and then to the exit opening, and means for delivering fuel to the interior of the passage at the upper end of the first stretch, the movement of the burning gases along the doubled back section serving to heat the sections where the fuel and air enter and are mixed. 80

2. A liquid fuel burner comprising a hollow body of refractory material partitioned to provide a continuous relatively long tortuous passage with an air entrance opening in the bottom wall and an exit opening in another wall, the passage extending from the air entrance opening upwardly to the top end, then downwardly to within a short distance of the bottom end, then back between and along the first two stretches in a reverse direction until it reaches the bottom wall, and then to the exit opening, and means for delivering fuel to the interior of the passage at the upper end of the first stretch, the movement of the burning gases along the doubled back section serving to heat the sections where the fuel and air enter and are mixed, said body having a removable wall section providing communication with the first upward stretch of the passage for the initial ignition of the fuel. 90

3. A liquid fuel burner comprising a hollow body of refractory material partitioned to provide a continuous relatively long tortuous passage with an air entrance opening in the bottom wall and an exit opening in another wall, the passage extending from the air entrance opening upwardly to a point adjacent the top end, then laterally a short distance, then downwardly for some distance, then backwardly in a reverse direction between the vertically extending 105 110 115 120 125 130

stretches, and along the preceding sections with only a dividing wall between them, then to the exit opening, and means for delivering liquid fuel upon the bottom wall 5 of the said lateral stretch where it mixes with air entering the passage from the bottom opening and burns.

4. A liquid fuel burner comprising a hollow body of refractory material partitioned 10 to provide a continuous relatively long tortuous passage with an air entrance opening in the bottom wall and an exit opening in another wall, the passage extending from the air entrance opening upwardly to a point 15 adjacent the top end, then laterally a short distance, then downwardly for some distance, then backwardly in a reverse direction between the vertically extending stretches, and along the preceding sections 20 with only a dividing wall between them, then to the exit opening, and means for delivering liquid fuel upon the bottom wall of the said lateral stretch where it mixes 25 with air entering the passage from the bottom opening and burns, said body having a removable wall section providing communication with the passage at approximately the junction between the first upward

stretch and the lateral stretch for the initial ignition of the fuel.

5. A liquid fuel burner comprising a hollow body of refractory material partitioned to provide a continuous relatively long tortuous passage with an air entrance opening in the bottom wall and an exit opening in 35 another wall, the passage extending from the air entrance opening upwardly to a point adjacent the top end, then laterally a short distance, then downwardly for some distance, then backwardly in a reverse direction 40 between the vertically extending stretches, and along the preceding sections with only a dividing wall between them, then to the exit opening, and means for delivering liquid fuel upon the bottom wall 45 of the said lateral stretch where it mixes with air entering the passage from the bottom opening and burns, said body being composed of superposed separable elements whereby when the elements are separated, 50 all parts of the passage will be readily accessible.

In witness whereof, I hereunto subscribe my signature.

TOIMI A. NISSINEN.
